UNITED STATES PATENT OFFICE.

SAMUEL JOEL, OF NEW YORK, N. Y.

HOLDER FOR THE SETTING OF STONES.

SPECIFICATION forming part of Letters Patent No. 319,095, dated June 2, 1885.

Application filed December 15, 1884. (No model.)

To all whom it may concern:

Be it known that I, SAMUEL JOEL, of the city and State of New York, have invented an Improvement in Holders for the Settings of Stones, of which the following is a specification.

In Letters Patent No. 289,106, granted to me, a holder for the settings of stones is shown possessing the general features of my present invention; but I have modified and improved it in the particulars hereinafter set forth, so that it is more easily handled by the workman while finishing the metallic setting, and adapting the same to the stone that is to be received thereinto.

In the drawings, Figure 1 is an elevation of the holder. Fig. 2 is a section in an enlarged size, and Fig. 3 is an end view.

At the end of the holder *a* there is a shoulder, *b*, turned in the metal, and the reduced portion is adapted to enter the opening at the back of the setting *c*, the setting itself resting upon the shoulder *b*, as in my aforesaid patent, and the holder is provided with longitudinal incisions *i*, as in my aforesaid patent; but I prefer that these incisions cross each other, as seen in Fig. 3, to render the holder more elastic.

I make the holder *a* tubular, and provide a head, *d*, at the back end.

The rear portion of the tubular holder is made with an internal screw-thread at *o*, and the central hole is tapering at the front end, as at *l*.

I provide a handle, *m*, preferably of wood,

and a rod, *n*, set into and projecting from, and entering the tubular holder *a*. The rod has a screw-thread, *r*, fitting the female screw *o*, and the end of this rod is tapering.

After the setting *c* has been placed upon the shoulder of the holder, the rod *n* is revolved within the holder and the screw forces the tapering end into the tapering portion *l* of the holder, and expands the ends of the holder as to hold the setting in the most firm and reliable manner while it is being finished and prepared for the reception of the stone.

When the setting is to be removed from the holder, the latter is loosened rapidly by unscrewing the tapering-ended rod *n*.

I claim as my invention—

1. The combination, with the split tubular holder *a*, having the shoulder *b*, of a rod having a tapering end, introduced within the tubular holder and acting to expand the holder for retaining the setting, substantially as set forth.

2. The combination, with the tubular holder *a*, having the shoulder *b*, and into which a screw-thread, *o*, of the rod *n*, having a tapering end and a screw at *r*, and the handle into which the rod *n* is fastened, substantially as set forth.

Signed by me this 11th day of December, 1884.

SAMUEL JOEL
